ABSTRACT

A two liquid-phase type liquid cosmetic composition of an attractive appearance is provided. The cosmetic composition comprises: (1) oil; (2) an organic liquid miscible with water; (3) water, and; (4) finely divided solid particles insoluble in any of the above ingredients (1), (2) and (3). The oil is dispersed in the form of spheres in a homogeneous mixture of the organic liquid and water. The solid particles are substantially absorbed on the interface between the oil phase and the homogeneous mixture phase of the organic liquid and water.

LIQUID COSMETIC COMPOSITION OF A TWO-PHASE TYPE

This invention relates to a liquid cosmetic composition of an attractive appearance.

In general cosmetics involve both ingredients of oil and water. In order to prepare and emulsion or other uniform dispersion from the two ingredients immiscible with each other, nonionic surface active compounds and other surface active compounds have heretofore been employed as an emulsifier or solubilizer. However, conventional cosmetics having, incorporated therein, these surface active compounds have some of the following disadvantages.

1. Some surface active compounds cause skin- or eyelid-irritation or inflammation.

2. Some surface active compounds tend to decompose thereby deteriorating the cosmetics and emitting an offensive odor.

3. When an ingredient other than oil, water and a surface active compound is present in the cosmetic composition, the composition becomes unstable, which leads to phase separation. This is a frequent phenomenon in the employment of most surface active compounds. Accordingly, it is very difficult to find a suitable surface active compound.

4. Surface active compounds cause undesirable foaming in cosmetics such as hair tonic and face lotion. This phenomenon is anything but agreeable.

5. Most surfaces active compounds diminish the effects of antiseptic, colorant and perfume components.

6. Even when a surface active compound is employed, the amount of oil capable of being incorporated into the cosmetic is restricted, i.e. it is difficult to obtain a liquid cosmetic composition rich in oil.

In order to minimize these troubles, a cosmetic has been proposed which contains a very limited amount of a surface active compound. This cosmetic comprises two different liquid phases, i.e. an oily phase and an aqueous phase, separated above and below because of insufficient capability of forming a homogeneous mixture. Obviously, such an above and below separated two phase type liquid cosmetic is inferior in capability of being readily mixed into a homogeneous mixture by shaking. Therefore, when the cosmetic is repeatedly used, the upper oily portion initially tends to be consumed in an amount larger than that of the below aqueous phase. Further, since the cosmetic contains a surface active compound, even though only a minor amount, the troubles listed above cannot be completely avoided.

Some conventional liquid cosmetics contain water-insoluble finely divided solid particles. However, these also need the incorporation of a surface active compound to impart the capability of the solid particles being uniformly dispersed by shaking. Unless a surface active compound is incorporated into this type of liquid cosmetic, the solid particles inevitably form a precipitate or coagulation. Therefore, these conventional liquid cosmetics also have the disadvantages set forth above.

It is, therefore, an object of the present invention to provide a liquid cosmetic composition which does not have the disadvantages caused by a surface active compound, as set forth above.

Another object of the present invention is to provide a two-phase type liquid cosmetic composition which

exhibits improved capability of readily forming a substantially homogeneous mixture by shaking, although the liquid cosmetic composition contains no surface active compound, and also exhibits an improved capability of being readily restored to the original state after the use.

Still another object of the present invention is to provide a liquid cosmetic composition having an attractive appearance.

10 A further object of the present invention is to provide a liquid cosmetic composition which can be prepared from a great variety of oils and oily materials.

Other objects and advantages of the present invention will be apparent from the following description.

15 In accordance with the present invention, there is provided a liquid cosmetic composition of two phase liquid type comprising:

(1) oil; (2) an organic liquid miscible with water; (3) water and; (4) finely divided solid particles insoluble in either of said oil, organic liquid and water and having an average particle size of no greater than 100 μ . Said oil is dispersed in the form of spheres in a homogeneous mixture of said organic liquid and water. Said finely divided solid particles are adsorbed on the interface between said oil and said homogeneous mixture of said organic liquid and water.

25 The liquid cosmetic composition of the present invention comprises two different liquid phases. One phase is a homogeneous mixture of an organic liquid, and water. The organic liquid is miscible with water but is substantially immiscible with oil. The other phase is oil in the form of spheres dispersed in the homogeneous mixture set forth above. The oil spheres dispersed in the homogeneous mixture of the organic liquid and water may be transparent, opaque, translucent or of a pearl-like appearance. The number of the oil spheres can be voluntarily varied, and ranges from one to thousands or more per litre of the liquid cosmetic composition. The diameter of the oil spheres range from 0.1 mm to several centimeters.

30 The liquid cosmetic composition of the present invention has the following advantages:

1. This liquid cosmetic composition contains no surface active agent and, therefore, it is possible to avoid the troubles caused by a surface active agent as set forth above.

35 2. Although this liquid cosmetic composition contains no surface active agent, it exhibits capability over conventional liquid cosmetics of forming a substantially homogeneous mixture when shaken by hand at the time of use.

40 3. A great variety of oils can be employed for the preparation of this liquid cosmetic composition. Therefore, an oil ingredient to be employed can be chosen without difficulty.

45 4. Finely divided solid particles are adsorbed on the whole interface between the oil phase and the aqueous phase of the organic liquid. The solid particles are neither precipitated nor buoyed up.

50 60 Due to the existence of such solid particles, the dispersion of oil spheres in the aqueous phase is stable.

It has been found that the state of oil spheres dispersed in the aqueous phase is not varied even after being in settled storage over a period of 3 years.

65 65 This liquid cosmetic composition exhibits improved capability of readily forming a substantially homogeneous mixture when shaken at use, as compared to a conventional above and below separated two phase type

liquid cosmetic. Further, the liquid cosmetic composition also exhibits improved capability of being readily restored to the original state after the use.

5. The finely divided solid particles in the liquid cosmetic composition suppress the underside glare resulting from the oil ingredient at the time of use. Further, the solid particles exhibit a skin-astringent effect and a sunlight-screening effect. When a medicine is absorbed on the solid particles, the resulting particles have a medicinal effect.

6. The liquid cosmetic composition is of an attractive appearance. Oil spheres dispersed in the aqueous phase may be transparent, translucent or pearl-like in appearance. These may possess any color. The size and the number of the oil spheres may be varied.

Therefore, a great variety of cosmetic can be provided. This is obviously advantageous from the viewpoint of merchandizing, because these liquid cosmetic can be distinguished according to the intended use. For example, liquid cosmetics containing a relatively large number of oil spheres can be readily recognizable as being for a dry skin use while those of a relatively small number of oil spheres for a normal skin, and so forth.

Oils used in the present invention are those which are liquid at room temperatures, immiscible with water, and have a specific gravity smaller than that of water. For example, oils include preferably high-molecular weight hydrocarbons such as liquid paraffin (a hydrocarbon oil consisting mainly of alkyl naphthalene), squalane (2, 6, 10, 15, 19, 23-hexamethyltetrasane) and the like; mono- or di-esters of fatty acid such as 2-hexyldecel palmitate, 2-octyldodecyl myristate, di-2-hexyldecel adipate, di-2-ethylhexyl sebacate and the like; vegetable and animal oils, i.e. triglycerides of fatty acid, such as olive oil, tsukaki oil, mink oil and the like; higher fatty acids having 10 to 25 carbon atoms such as isostearic acid, oleic acid and the like; fatty alcohols having 10 to 25 carbon atoms such as oleyl alcohol; and synthetic oils such as silicone oil, polyalkylene glycol derivatives and the like. The polyalkylene glycol derivatives include, for example, Unilube MB-370 (Bu-O-CH(CH₃)-CH₂-O-_nH, n=40, trade name made by NIHON YUSHI K. K., Japan). These oils can be used either alone or in a combination of at least two. Oily solid substances such as wax, i.e. an ester of a high-molecular weight fatty acid with a high-molecular weight fatty alcohol, and fat, i.e. a triglyceride of a high-molecular weight fatty acids, may be dissolved in the oil used in the present invention.

The amount of oil present in the liquid cosmetic composition may be varied within the range of lower than approximately 95% by weight, preferably lower than 60% by weight.

Finely divided solid particles used in the present invention are those which have an average particle size of below approximately 100 μ , are pharmaceutically non-toxic to the skin, and insoluble in both oil and the homogeneous mixture of water and the organic liquid. Preferable finely divided solid particles include those of, for example, natural inorganic substances such as talc, kaolin, and the like; artificial inorganic substances such as iron oxide, magnesium oxide, zinc oxide, zinc peroxide, titanium oxide, calcium carbonate (prepared and precipitated), calcium secondary phosphate, aluminum hydroxide, antimony oxide, alumina, barium sulfate; inorganic pearl-like substances (bismuth oxychloride, titania), silicic acid anhydride, magnesium metasilicate aluminate ($MgO \cdot Al_2O_3 \cdot 2SiO_2$), silica-

alumina, and the like; natural organic substances such as protein, microcrystalline cellulose, fish scale, pearl and the like; and artificial organic substances such as high polymeric substances, e.g. polyvinyl chloride, nylon-12 (poly- Ω -lauryllactam H-NH-(CH₂)₁₁-CO] _nOH), and the like; organic pigments and lakes, e.g. Permanent Orange (see Colour Index, Pigment Orange 5, 12075) and Lithol Rubine BCA (Trade name, made by BASF, Germany). These finely divided solid particles may be coated with suitable substances such as, for example, metal soaps, surfactants and polymers. These solid particles may be used either alone or in combination.

15 The amount of the finely divided solid particles present in the liquid cosmetic composition may be varied within the range of lower than approximately 50% by weight.

16 Organic liquids used in the present invention are pharmaceutically non-toxic to the skin, and miscible 20 with water, but substantially immiscible with the oil set forth above. The organic liquids may be either completely immiscible, or slightly miscible with the oil if the homogeneous mixture of the organic liquid with water is immiscible with the oil. Further, the organic liquid 25 has in usual a specific gravity of lower than 1.0.

The organic liquid include, for example, monohydric alcohols having carbon atoms of no greater than 5 such as ethyl alcohol, isopropyl alcohol and tetrahydrofurfuryl alcohol; polyhydric alcohols such as those having 30 carbon atoms of no greater than 6, for example, propylene glycol, glycerin, sorbitol, dipropylene glycol, 1,3-butylene glycol and mannitol, and polyethylene glycol having carbon atoms of no greater than 50; ethers having carbon atoms of no greater than 6 such as diethylene glycol ethyl ether, ethyl ether, dioxane and tetrahydrofuran; ketones having carbon atoms of no greater than 6 such as acetone and N-methylpyrrolidone. Of these organic liquids, ethyl alcohol, isopropyl alcohol and N-methylpyrrolidone are most preferable.

40 The homogeneous mixture of water and the organic liquid present in the liquid cosmetic composition may be varied within the range of lower than approximately 95% by weight.

In the liquid cosmetic composition of the present invention, oil ingredient, in the form of small spheres, are dispersed in a homogeneous mixture of water and the organic liquid. In order to prepare the stable dispersion of the oil spheres in the homogeneous mixture of water and the organic solvent, the following prerequisites 50 should be satisfied.

1. The difference in specific gravity between the oil ingredient (d_o) and the homogeneous mixture (d_w) of water and the organic liquid is zero or nearly zero.

$$d_o - d_w \approx 0$$

A permissible range of the difference varies depending upon the temperature. However, in general, the absolute value of the difference may be not greater than 0.04.

$$|d_o - d_w| \leq 0.04$$

60 2. Spreading coefficient (S) defined by the following equation is negative.

$$S = \gamma_w - \gamma_o - \gamma_{ow} < 0$$

65 wherein γ_o is a surface tension of the oil ingredient, γ_w is a surface tension of a homogeneous mixture of water and the organic liquid, and γ_{ow} is an interfacial tension

between the oil ingredient and the homogeneous mixture of water and the organic liquid.

If spreading coefficient is zero or positive, oil spheres break, when buoyed up to the surface, to form an above and below separated two-phase type liquid. This two-phase liquid is not restored to the original state.

3. Oil and the homogeneous mixture are immiscible with each other.

In order to balance the specific gravity between the oil and the homogeneous mixture of water and the organic liquid, the particular organic solvent to be mixed with water and the proportion of the amount thereof to the amount of water should be suitably determined depending upon the specific gravity of the particular oil used. For example, when a liquid paraffin having a specific gravity of d_{40}^{30} 0.8470 is employed as an oil ingredient, a homogeneous mixture of the same specific gravity can be prepared by blending 25% by weight of water and 75% by weight of ethyl alcohol having a specific gravity of d_4^{30} 0.7808.

When finely divided solid particles having a relatively large particle size, i.e. 10μ - 100μ , are employed, the specific gravity should preferably be completely balanced between the oil and the homogeneous mixture of water and the organic liquid. However, the smaller the particle size of the solid particles, the greater the warrantable difference in specific gravity between the oil and the homogeneous mixture.

In one modified embodiment of the liquid cosmetic composition of the present invention, the liquid cosmetic composition is composed of oil, an organic liquid miscible with water and finely divided solid particles, i.e. water can be omitted from the cosmetic composition, if the prerequisites set forth above are satisfied, as exemplified in Example 1 below.

Further, the following factors should preferably be taken into consideration for ensuring good dispersibility when shaken, good reproducibility of the dispersion after shaking is stopped and a reasonably high reproduction speed of the dispersion after shaking is stopped.

The dispersibility when shaken depends upon the interfacial tension between the oil and the aqueous mixture, the viscosity of the oil and the shaking force. Reproducibility of the dispersion after shaking is stopped depends upon the joining speed of oil spheres dispersed, the polarity of oil, the miscibility between oil and the aqueous mixture, and the solubility between oils when two or more oils are employed. Reproduction speed of the dispersion after shaking is stopped depends upon the joining speed of oil spheres, the difference in specific gravity between oil and the aqueous mixture, the temperature, and the viscosity of the aqueous mixture.

The relationship between physical characteristics of finely divided solid particles and the shape of the oil spheres dispersed in the homogeneous mixture of water and organic liquid will be illustrated with reference to the accompanying drawings.

FIGS. 1A and 1B show model pictures of the microscopic photograph of the interfacial portion between the oil phase and the aqueous phase consisting of a homogeneous mixture of water and the organic liquid, and the appearance of the waterorganic liquid-solid particles-oil system, respectively, when hydrophilic, finely divided solid particles are employed.

FIGS. 2A and 2B, 3A and 3B, and 4A and 4B, show similar model pictures when slightly hydrophilic,

slightly oleophilic and oleophilic, finely divided solid particles are employed, respectively.

As shown in FIGS. 1A and 1B, when the finely divided solid particles employed are hydrophilic, the particles 1 are dispersed in an aqueous liquid phase 2, but not in an oil phase 3, and gradually settle to the bottom of the aqueous liquid phase 2 to form a sediment 4. Therefore, hydrophilic solid particles are unsuitable for the provision of the cosmetic composition of the present invention.

When the solid particles are slightly hydrophilic, these solid particles 1 are adsorbed on the interface of oil spheres 3 and thereby the oil spheres 3 are stably dispersed in an aqueous phase 2, as shown in FIGS. 2A and 2B. The number and the size of the oil spheres 2 may be varied depending upon the amount of the solid particles employed.

When the solid particles are slightly oleophilic, the solid particles 1 are adsorbed on an inside of the surface of oil spheres 3, and the oil spheres 3 are unstable and tend to unite with each other, as shown in FIGS. 3A and 3B. The united oil sphere 3' exhibits an intricate shape and a creased surface with wrinkles. Therefore, finely divided solid particles should preferably possess a hydrophilic property slightly stronger than or well-balanced with an oleophilic property.

When the solid particles are oleophilic, these particles 1 are dispersed within an oil sphere 3, as shown in FIGS. 4A and 4B.

Hydrophilic characteristics of the solid particles may be expressed in terms of a sedimentation volume per unit of apparent specific volume (hereinafter referred to as fw for brevity) of the solid particles in water, or a hydrophilic coefficient of the solid particles.

When finely divided hydrophilic solid particles are dispersed in water, these particles form a relatively uniform dispersion. In contrast, when finely divided oleophilic solid particles are dispersed in water, these particles do not form a uniform dispersion but partially coagulate. In other words, in water the hydrophilic solid particles exhibit a small sedimentation volume, but the oleophilic solid particles exhibit a large sedimentation volume. Therefore, fw may be one of the yardsticks for determining the hydrophilic property. The fw in water is represented by the formula:

$$fw = \text{sedimentation volume in water (in cc/g)} / \text{apparent specific volume (in cc/g)}$$

The sedimentation volume in water and the apparent specific volume are determined as follows.

1. Sedimentation volume

A finely divided solid particle specimen is heated at 105°C for 2 hours, cooled, and then weighed. The specimen is dispersed in an aqueous 20% ethyl alcohol solution. After the dispersion is deaired by vacuuming at a pressure of 4 to 5 mmHg, the dispersion is settled in a settling tube over a period of one month. Then, the sedimentation volume is measured.

2. Apparent specific volume

A finely divided solid particle specimen is heated, cooled and weighed in the same manner as described above. A slender glass tube is then filled with approximately 20 g of the specimen. After that, the glass tube is repeatedly dropped 400 times from a height of 4 cm.

65 Then, the apparent specific volume is measured.

Sedimentation volume, apparent specific volume and fw of some finely divided solid particles are exemplified in Table I.

Table I

No.	Solid particle	Sedimentation volume in H ₂ O (cc/g)	Apparent specific volume (cc/g)	fw	Specific gravity*
1	Anhydrous silicic acid A	4.33	12.20	0.35	2.441

33	Lithol Rubine BCA	3.76	1.64	2.29	1.782
34	Polyvinyl chloride	1.37	—	—	1.460

Note: Determined on specimen after heating at 105°C for 2 hours.

Alternatively, hydrophilic characteristics of the solid particles may be expressed in terms of hydrophilic coefficient. The hydrophilic coefficient is represented by the ratio of S_{H_2O}/S_{N_2} , wherein S_{H_2O} and S_{N_2} are the surface areas determined from adsorption isotherms of water and gaseous nitrogen on the solid particles, respectively, plotted according to Brunauer-Emmett-Teller equation. The larger the hydrophilic coefficient, the greater the hydrophilic property of the solid particles.

Hydrophilic coefficient of some finely divided solid particles are exemplified in Table II.

Table II

No.	Solid Particle	S_{N_2} (m ² /g)	S_{H_2O} (m ² /g)	S_{H_2O}/S_{N_2}
5	1 Colloidal kaolin	11.3	17.0	1.50

	10 Talc A	4.1	2.3	0.56
	11 Carbon black	215.8	97.7	0.45

The relationship between hydrophilic coefficient (S_{H_2O}/S_{N_2}) and sedimentation volume in water per unit of apparent specific volume (fw) is shown in FIG. 5. Numerical references indicated in FIG. 5 correspond to those of specimens shown in Table II. As apparent from FIG. 5, S_{H_2O}/S_{N_2} and fw exhibit a negative interrelationship.

The relationship between specific gravity and fw is shown in FIG. 6. Finely divided solid particles having a specific gravity and an fw, both falling within the area expressed with hatching in FIG. 6 are preferably employed for the preparation of the liquid composition of the present invention. FIG. 6 has been drawn on various solid particle specimens in the case where a di-2-hexyldecyl adipate-water-ethyl alcohol combination was employed. However, a similar tendency has been observed in the case where other combinations were employed.

With reference to the above considerations, finely divided solid particles suitably employed in the present invention will be easily chosen. Preferable solid particles depend upon the particular oil and the particular liquid miscible with water. For example, finely divided solid particles having an fw falling within the range of 0.5 to 3.5 are suitable for the combination of liquid paraffin and an aqueous ethyl alcohol solution of a 78% concentration. When finely divided solid particles do not have an fw falling within the above range, a stable liquid composition wherein oil spheres are dispersed is not obtainable. That is, the solid particles settle down, and the oil phase and the aqueous phase separate from each other above and below. Otherwise, the liquid composition becomes cloudy, or oil spheres dispersed in the aqueous phase tend to be incorporated with each other.

The number and size of oil spheres dispersed in the aqueous phase can be easily varied by controlling the amount of finely divided solid particles and oil employed. The size of oil spheres may be varied within the range of 0.1 mm to 1.0 cm or more, preferably 1.0 mm to 5.0 mm, as expressed in diameter.

The manner of preparation of the two-phase type liquid cosmetic composition of the present invention is not critical. Four ingredients, oil, water, the organic liquid and finely divided solid particles may be blended with each other concurrently or sequentially in any order, by using a conventional blending device. However, the liquid cosmetic composition is preferably prepared in the following manner. First, water and the organic liquid miscible with water are mixed with each other to prepare the homogeneous mixture, followed by the addition of finely divided solid particles. Then, oil is

added to the mixture followed by agitation. The resulting mixture is left to settle over a stated period, e.g. one day.

The two-phase type liquid cosmetic composition of the present invention may contain additives such as, for example, colorant, perfume, antioxidant, ultraviolet ray absorber, antiseptic, wetting agent, astringent, or other cosmetic base. The liquid cosmetic composition has a wide variety of uses as hair or skin cosmetics such as hair tonic or lotion, skin lotion or toilet water.

The invention will now be illustrated with reference to Examples. In the Examples, all parts are parts by weight.

EXAMPLE 1

0.03 part of talc powder having an fw of 2.12 (made by NIHON BIRYUSHI KOGYO, Japan) was incorporated into 90.0 parts of ethyl alcohol. To the mixture, 10.0 parts of squalane ($C_{30}H_{62}$, made by NIKKO CHEMICALS CO., Japan) was added followed by agitation. The mixture was settled over a period of one day. A liquid composition of attractive appearance was obtained wherein small translucent spheres of squalane were dispersed.

EXAMPLE 2

55.51 parts of ethyl alcohol and 7.41 parts of polyethylene glycol having a molecular weight of approximately 300 were mixed with 18.55 parts of water. To the mixture, 0.01 part of magnesium metasilicate aluminate powder, $MgO \cdot Al_2O_3 \cdot 2SiO_2$ (trade name, Neusilin made by FUJI KAGAKU KOGYO, CO., Japan) and 18.52 parts of di-2-hexadecyl adipate (trade name, Eshelan 201 made by Nihon Shono Co., Japan) were added in order followed by agitation. The mixture was settled over a period of one day. A liquid composition of attractive appearance was obtained wherein small transparent spheres of di-2-hexadecyl adipate were dispersed.

EXAMPLE 3

A liquid composition was prepared in the manner similar to that described in Example 2 from the following ingredients.

Liquid paraffin (viscosity 150 sec/30°C, trade name, Union SHP-280 made by Union Yushi Co., Japan)	9.90	parts
Ethyl alcohol	67.16	"
Water	23.73	"
Antimony oxide (fw 2.28)	0.02	"

The liquid composition so prepared was of attractive appearance wherein relatively small white spheres of liquid paraffin were dispersed.

EXAMPLE 4

A liquid composition was prepared in the manner similar to that described in Example 2 from the following ingredients.

di-2-Hexadecyl adipate	10.0	parts
Ethyl alcohol	57.79	"
Water	32.21	"
Sodium chloride	0.1	"
Bismuth oxychloride (indicated in Table I as sample No. 27)	0.02	part

10 The liquid composition so prepared was of attractive appearance wherein small pearl-like spheres of di-2-hexadecyl adipate were dispersed, as shown in FIG. 7.

EXAMPLE 5

A liquid composition was prepared in the manner similar to that described in Example 2 from the following ingredients.

Liquid paraffin	50.0	parts
Ethyl alcohol	41.32	"
Water	8.68	"
Sodium chloride	0.1	"
Fish scale powder	0.08	"

20 The liquid composition so prepared was of attractive appearance wherein small pearl-like spheres of liquid paraffin were dispersed.

EXAMPLE 6

25 A liquid composition was prepared in the manner similar to that described in Example 2 from the following ingredients.

di-2-Hexadecyl adipate	47.61	parts
Ethyl alcohol	35.68	"
Water	11.93	"
Polyethylene glycol (molecular weight approximately 300)	4.76	"
Magnesium metasilicate aluminate	0.03	"

40 The liquid composition so prepared was of attractive appearance wherein small transparent spheres of di-2-hexadecyl adipate were dispersed, as shown in FIG. 8.

EXAMPLE 7

45 A liquid composition was prepared in the manner similar to that described in Example 2 from the following ingredients.

Liquid paraffin	24.02	parts
Ethyl alcohol	59.17	"
Water	1.593	"
Bismuth oxychloride	0.07	"

The liquid composition so prepared was of attractive appearance wherein relatively small pearl-like spheres of liquid paraffin were dispersed, as shown in FIG. 9.

EXAMPLE 8

60 A liquid composition was prepared in the manner similar to that described in Example 1 from the following ingredients.

Squalane	10.0	parts
Ethyl alcohol	90.0	"
Bismuth oxychloride	0.01	"

11

The liquid composition so prepared was of attractive appearance wherein relatively large pearl-like spheres of squalane were dispersed, as shown in FIG. 10.

EXAMPLE 9

A liquid composition was prepared in the manner similar to that described in Example 2 from the following ingredients.

Liquid paraffin	12.5	parts
di-2-Hexadecyl adipate	12.5	"
Ethyl alcohol	54.87	"
Water	20.13	"
Bismuth oxychloride	0.04	"

The liquid composition so prepared was of attractive appearance wherein small pearl-like spheres of liquid paraffin and di-2-hexadecyl adipate were dispersed, as shown in FIG. 11.

EXAMPLE 10

A liquid composition was prepared in the manner similar to that described in Example 2 from the following ingredients.

di-2-Hexadecyl adipate	25.0	parts
Liquid paraffin	25.0	"
Ethyl alcohol	36.58	"
Water	13.42	"
Nylon 12 (made by Toray Industries Inc., Japan)	0.06	"

The liquid composition so prepared was attractive appearance wherein relatively small translucent spheres of di-2-hexadecyl adipate and liquid paraffin were dispersed, as shown in FIG. 12.

EXAMPLE 11

A liquid composition was prepared in the manner similar to that described in Example 2 from the following ingredients.

di-2-Hexadecyl adipate	25.0	parts
Ethyl alcohol	48.16	"
Water	26.84	"
Sodium chloride	0.1	"
Titanium dioxide powder (particle size, approximately 30 μ)	0.01	"

The liquid composition so prepared was of attractive appearance wherein small translucent spheres of di-2-hexadecyl adipate were dispersed.

EXAMPLE 12

A liquid composition was prepared in the manner similar to that described in Example 2 from the following ingredients.

Liquid paraffin	5.0	parts
Oleyl alcohol	5.0	"
Ethyl alcohol	79.58	"
Water	10.42	"
Talc (indicated in Table I as sample No. 13)	0.02	"

12

The liquid composition so prepared was of attractive appearance wherein very small translucent spheres of liquid paraffin and oleyl alcohol were dispersed, as shown in FIG. 13.

EXAMPLE 13

A liquid composition was prepared in the manner similar to that described in Example 2 from the following ingredients.

di-2-Hexadecyl adipate	18.52	parts
Isopropyl alcohol	55.60	"
Water	18.64	"
Polyethylene glycol (molecular weight, approximately 300)	7.41	"
Magnesium metasilicate aluminate	0.01	"

The liquid composition so prepared was of attractive appearance wherein small transparent spheres of di-2-hexadecyl adipate were dispersed.

What we claim is:

1. A liquid cosmetic composition of a two phase type, which comprises:
  1. up to about 95% by weight of an aqueous phase substantially comprised of water and at least one organic liquid selected from the group consisting of ethyl alcohol, N-methyl pyrrolidone and isopropyl alcohol,
  2. up to about 95% by weight of an oil phase in the form of spheres having diameters of 0.1 mm to 1.0 cm dispersed in said aqueous phase, said oil phase being substantially comprised of at least one member selected from the group consisting of liquid paraffin, squalane, 2-hexyldecyl palmitate, 2-octyl-dodecyl myristate, di-2-hexyldecyl adipate, di-2-ethylhexyl sebacate, olive oil, tsubaki oil, mink oil, isostearic acid, oleic acid, oleyl alcohol and a polypropyleneglycol butyl ether having a polymerization degree of approximately 40, and
  3. not greater than approximately 50% by weight of finely divided solid particles insoluble in the liquid ingredients (1) and (2) set forth above, said solid particles having particle sizes of less than about 100 micron and being adsorbed on the interface between said aqueous phase (1) and said oil phase (2), said solid particle being selected from at least one member selected from the group consisting of talc, kaolin, iron oxide, magnesium oxide, zinc oxide, zinc peroxide, titanium oxide, precipitated calcium carbonate, calcium secondary phosphate, aluminium hydroxide, antimony oxide, alumina, barium sulfate, silicic acid anhydride, magnesium metasilicate aluminate, silica-alumina, bismuth oxychloride, microcrystalline cellulose, fish scale, polyvinyl chloride and poly- Ω -lauryllactam
- the proportion in the amount of water to the organic liquid in said aqueous phase (1) being such that the difference in specific gravity between said aqueous phase (1) and said oil phase (2) is not greater than 0.04 and wherein a spreading coefficient S defined as having the following formula is negative,

$$S = \gamma_w - \gamma_o - \gamma_{ow}$$

wherein γ_o and γ_w are surface tensions of the oil and the homogeneous mixture of water and the organic liquid respectively, and γ_{ow} is an interfacial tension between

the oil and the homogeneous mixture of water and the organic liquid.

2. A liquid cosmetic composition according to claim 1 wherein said oil phase is present in an amount of less than 60% by weight based on the weight of the cosmetic composition.

3. A liquid cosmetic composition of a two phase type, according to claim 1 which consists essentially of:

1. not more than approximately 95% by weight of an aqueous phase substantially comprised of water and at least one organic liquid selected from the group consisting of ethyl alcohol and isopropyl alcohol,
2. less than 60% by weight of an oil phase in the form of spheres of 0.1 mm to 1.0 cm diameter dispersed in said aqueous phase, said oil phase being substantially comprised of at least one member selected from the group consisting of liquid paraffin, di-2-hexyldecyl adipate, squalane and oleyl alcohol, and
3. not more than approximately 50% by weight of finely divided solid particles insoluble in the liquid ingredients (1) and (2) set forth above, said solid particles having particle sizes smaller than approximately 100 microns and being adsorbed on the interface between said aqueous phase (1) and said oil phase (2) and being at least one member selected from the group consisting of precipitated calcium carbonate, zinc oxide, zinc peroxide, talc, bentonite, iron oxide, antimony oxide, magnesium metasilicatealuminate, bismuth oxychloride, fish scale and poly- Ω -lauryllactam, the proportion in the amount of water to the organic liquid in said aqueous phase (1) being such that the difference in specific gravity between said aqueous phase (1) and said oil phase (2) is not greater than 0.04 and wherein a spreading coefficient S defined as having the following formula is negative,

$$S = \gamma_w - \gamma_o - \gamma_{ow}$$

wherein γ_w and γ_o are surface tensions of the oil and the homogeneous mixture of water and the organic liquid, respectively, and γ_{ow} is an interfacial tension between the oil and the homogeneous mixture of water and the organic liquid.

4. A liquid cosmetic composition of a two phase type, according to claim 1 which consists essentially of:

1. not more than approximately 95% by weight of an organic liquid phase comprising at least one member selected from the group consisting of ethyl alcohol and isopropyl alcohol,
2. not more than approximately 95% by weight of an oil phase in the form of spheres of 0.1 mm to 1.0 cm diameter dispersed in said organic liquid phase, said oil phase comprising at least one member selected from the group consisting of liquid paraffin, squalane, 2-hexyldecyl palmitate, 2-octyldecyl myristate, di-2-hexyldecyl adipate, di-2-ethylhexyl sebacate, olive oil, tsbaki oil, mink oil, isostearic acid, oleic acid, oleyl alcohol, and a polypropylene glycol butyl ether having a polymerization degree of approximately 40, and
3. not more than approximately 50% by weight of finely divided solid particles insoluble in the liquid ingredients (1) and (2) set forth above, said solid particles having particle sizes of less than 100 microns approximately and being adsorbed on the interface between said organic liquid phase (1) and said oil phase (2), and being at least one member selected from the group consisting of talc, kaolin, iron oxide, magnesium oxide, zinc peroxide, titanium oxide, precipitated calcium carbonate, calcium secondary phosphate, aluminium hydroxide, antimony oxide, alumina, barium sulfate, silicic acid anhydride, magnesium metasilicatealuminate, silica-alumina, bismuth oxychloride, microcrystalline cellulose, fish scale, pearl, polyvinyl chloride and poly- Ω -lauryllactam,

the difference in specific gravity between said organic liquid (1) and said oil (2) being not greater than 0.04 and wherein a spreading coefficient S defined as having the following formula is negative,

$$S = \gamma_w - \gamma_o - \gamma_{ow}$$

- 40 wherein γ_w and γ_o are surface tensions of the oil and the homogeneous mixture of water and the organic liquid, respectively, and γ_{ow} is an interfacial tension between the oil and the homogeneous mixture of water and the organic liquid.
